The ornamental design for a manual can opener, as shown and described.

DESCRIPTION

FIG. 1 is a perspective view of the manual can opener showing my new design;
 FIG. 2 is a perspective view thereof from another angle;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof;
 FIG. 8 is a bottom plan view thereof;
 FIG. 9 is an enlarged view of a portion indicated with numeric 9 in FIG. 1; and,
 FIG. 10 is a perspective view of the open state of FIG. 1. The dash-dot broken lines in the drawings illustrate portions of the article that form no part of the claimed design. The dash-dot broken lines in the drawings are included for the purpose of depicting the partial enlarged views and form no part of the claimed design.
